UNITED STATES PATENT OFFICE.

HERMAN E. VANCE, OF COLUMBUS, OHIO.

SLAT FOR CONSTRUCTING FIREPROOF BLINDS.

No. 800,249.

Specification of Letters Patent.

Patented Sept. 26, 1905.

Application filed February 8, 1905. Serial No. 244,724.

To all whom it may concern:

Be it known that I, HERMAN E. VANCE, a citizen of the United States, residing at Columbus, in the county of Franklin and State of Ohio, have invented certain new and useful Improvements in Slats for Constructing Fireproof Blinds; and I do declare the following to be a full, clear, and exact description of the invention, such as will enable others skilled in the art to which it appertains to make and use the same.

The object of this invention is to provide a slat for making up fire-resisting shutters, doors, curtains, and the like through which radiation of heat shall not be so great as through a curtain in which the slats are wholly of metal.

The invention is embodied in the improved construction hereinafter described and claimed.

In the accompanying drawings, Figure 1 is a transverse sectional view of a slat and two portions of slats joined thereto, as in a curtain. Fig. 2 is a like view showing how the body of the slat can be reinforced. Fig. 3 is a face view of a piece of slat looking at its inner or concaved side.

In the several views, 1 designates the body portion of the slat. This body portion is made in strip form, chiefly of papier-mâché, uralite, (the base of which is asbestos fiber,) or any other good non-metallic fire-resisting, non-radiating, slow-burning, or heat-retardent material that is adapted to be pressed, molded, or otherwise shaped to form such body portion; but in some instances to promote the integrity of the body material I propose to embed, mold, or otherwise secure in the body-strip a reinforcing-strip 1^a, as of wire-cloth, into the interstices of which the material of the body penetrates or mixes to form therewith a practically integral structure.

In the opposite edges of the body portion 1 of the slat are secured metallic strips 2 and 2^a, which can be bent to form hooks 20 and shoulders 21, standing across the mouths of the hooks like those illustrated in the United States Letters Patent issued to W. R. Kinnear, No.

572,014, dated November 24, 1896; but other means for joining the slats together can be used in connection with my improvement. These metallic hooking-strips can be embedded in or secured to the body portion of the slat at the time the body portion is made or they can be applied after they are made—as, for example, by inserting them in kerfs made in the edges of the body portion and securing them therein by rivets 3, as indicated in the drawings.

Some changes can be made without departing from the gist of the invention.

What I claim, and desire to secure by Letters Patent, is—

1. In a fireproof blind or curtain a slat having a body portion composed of non-metallic heat retardant or resisting material and its edges made of separate metallic devices added thereto for joining the slat to other slats.

2. In a fireproof blind or curtain a slat having a body portion composed chiefly of a non-metallic heat retardant or resisting material with a reinforcing material of metal embedded therein and its edges formed of separate metallic devices added thereto for joining the slat to other slats.

3. In a fireproof blind or curtain a slat having a body portion composed of a non-metallic heat retardant or resisting material and its edges made of separate metallic strips added thereto bent to form hooks for engagement with other slats.

4. In a fireproof blind or curtain a slat having a body portion composed of a non-metallic heat retardant or resisting material and provided at its edges with separate metallic strips added thereto each having one of its edges embedded in or secured to the body portion with the exposed portions bent to form hooks for engagement with other slats.

In testimony whereof I affix my signature in presence of two witnesses.

HERMAN E. VANCE.
